Attorney

UNITED STATES PATENT OFFICE.

JAMES R. CREIGHTON, OF CAMBRIDGE, ILLINOIS.

HEATER FOR AUTOMOBILES.

1,221,691.

Specification of Letters Patent.

Patented Apr. 3, 1917.

Application filed January 3, 1916. Serial No. 69,923.

To all whom it may concern:

Be it known that JAMES R. CREIGHTON, a citizen of the United States, residing at Cambridge, in the county of Henry and

5 State of Illinois, have invented certain new and useful Improvements in Heaters for Automobiles, of which the following is a specification, reference being had to the accompanying drawings.

10 This invention relates to heaters for automobiles and more particularly to a foot warmer of that type which is supplied with the heating medium from the engine exhaust pipe of the vehicle.

15 It is the primary object of the present invention to provide a heater for vehicles of the above type, which is so constructed and arranged that a maximum heating capacity is assured, while, at the same time, all 20 liability of burning the floor or bed of the machine or the shoes of the occupant, is obviated.

The invention has for another important 25 object to provide a heater of the above character having certain improved structural features whereby the escape of the exhaust gases from the hot air chamber of the heater into the interior of the vehicle will be effectively precluded.

30 It is still another object of the invention to provide a heater for motor vehicles, which is simple and durable in its construction, highly serviceable and convenient in practical use, and capable of manufacture at 35 relatively small cost.

With the above and other objects in view, my invention consists in the novel features of construction, combination and arrangement of parts to be hereinafter more fully 40 described, claimed and illustrated in the accompanying drawing, in which,

45 Figure 1 is a longitudinal sectional view through a heater constructed in accordance with the preferred embodiment of my invention;

Fig. 2 is a top plan view thereof partly in section;

Fig. 3 is a fragmentary sectional view similar to Fig. 1, with the cut-off valve 50 closed; and

Fig. 4 is a fragmentary transverse section taken on the line 4-4 of Fig. 1.

Referring in detail to the drawing, 5 designates the base plate of the heater proper 55 and 6 the upper or top plate which is formed adjacent its outer edge with an inclined

flange 7 having an annular laterally projecting rim 8. This rim rests upon the edge of the base plate 5 and is permanently welded to said base plate. The top plate 6 is 60 suitably spaced from the base plate 5 to provide the hot air chamber 9, and over this top wall and in spaced relation thereto, a protecting plate of sheet metal, indicated at 10, is arranged, said sheet metal plate being provided with a plurality of perforations, indicated at 11. In the accompanying drawing, I have shown the heater as of rectangular form in plan, and the protecting sheet metal plate or casing 10 is open at its 65 opposite ends. It will be understood, however, that the heater may also be constructed in various other forms or shapes. The longitudinal edge portions of the perforated protecting plate 10 are downwardly and 70 outwardly inclined, as at 12, and provided with outwardly projecting lateral flanges 13 which rest upon the rim 8 of the top wall 6 of the heater.

Upon the bottom face of the base plate 5, 80 a sheet of insulating material 14 is arranged, and an imperforate sheet metal plate 15 is engaged upon this sheet of insulating material and holds the same in place. The edges of this sheet metal plate are turned upwardly and inwardly over the wedged edges of the plates 5 and 6, and upon the flanges 13 of the plate 10 and tightly crimped thereon, thereby holding all parts in assembled relation and against relative movement. 85 The sheet 14 may be of asbestos or any other suitable insulating medium and it is provided for the purpose of preventing overheating and possible ignition of the wood floor of the vehicle. The plate 15, the insulating sheet 14 and the base wall 5 of the heater are provided adjacent their opposite ends with coinciding openings. An inlet pipe 16 is disposed through the openings at one end of the heater and securely welded or otherwise permanently fixed to the base wall 5. This pipe is connected by a length of flexible tubing 17 to an upwardly projecting nipple 18 suitably connected to the exhaust pipe E extending from the vehicle engine. In the nipple 18, a rotatable valve plate 19 is arranged and is adapted to open or cut off communication between the hot air chamber 9 of the heater and the exhaust pipe. To one end of the rod or shaft 19 of the valve plate 19, an arm 20 is attached, to which the lower end of the lever 21 is

pivots connected. The spring 22 is also attached at one end to the lower end of said lever and has its other end suitably fixed to the exhaust pipe, said spring normally acting to pull the lever 21 downwardly and hold the valve plate 19 in its closed position. The lever 21 is provided with a series of teeth indicated at 23, for engagement by a pivoted dog 24 suitably mounted on the floor 10 of the vehicle. By disengaging the dog 24 from the teeth 23 and pulling the lever 21 upwardly, the valve plate 19 may be moved to its open position and admit the exhaust from the pipe E to the pipe 16 and hence to 15 the chamber 9 of the heater. At the opposite end of the heater, the outlet pipe 25, extending upwardly through the vehicle floor and the opening in the base wall of the heater, is connected, preferably by welding 20 the end of the pipe to said base wall.

From the foregoing description, taken in connection with the accompanying drawing, the construction, manner of operation and several advantages of the invention will be 25 clearly and fully understood. The exhaust entering the chamber 9, in its passage therethrough highly heats the top wall 6 of the chamber before being discharged to the atmosphere from the outlet pipe 25, and thus 30 heat is given off from said wall through the openings in the plate 10 and the open ends of said protecting plate or housing. The feet placed upon this perforated plate will be comfortably heated but without danger 35 of burning the soles of the shoes. As before stated, the provision of the insulating sheet 14 also prevents overheating of the car floor. As the top and bottom plates of the heater 40 chamber are securely welded together, the chamber is rendered absolutely air-tight at its edges, so that the exhaust gases can only escape through the outlet pipe 25.

From the above, it will be seen that I have produced a very simply constructed, as 45 well as serviceable and convenient heater for motor vehicles, which may be readily applied to the ordinary automobile at minimum expense and without necessitating any material alterations in the construction 50 thereof. In actual practice, the device has been found well adapted for the purpose, as it will quickly heat the interior of the vehicle to a comfortable degree when communication is opened between the heater 55 chamber and the exhaust pipe. It is, of

course, apparent that the heater may be made in various sizes in accordance with the size and capacity of the machine. The device is also susceptible of many other modifications in the form, proportion and arrangement of the several structural features thereof and I, therefore, reserve the privilege of adopting all such legitimate changes as may be fairly embodied within the spirit and scope of the invention as claimed. 60

Having thus fully described my invention, what I desire to claim and secure by Letters Patent is:—

1. A heater of the character described comprising spaced top and bottom plates, 7 said top plate having marginal flanges permanently welded to the edges of the bottom plate, a perforated radiator plate open at its ends extending over and in spaced relation to the top plate, said radiator plate 75 having downwardly projecting, longitudinal flanges engaged upon the longitudinal edges of the top plate, an insulating sheet engaged upon the bottom face of the bottom plate, a sheet metal plate extending over the insulating sheet and having marginal portions thereof bent upwardly and inwardly upon the longitudinal flanges of the radiator plate to retain the latter in place, and means for supplying a heating medium to the space between said top and bottom plates. 80

2. A heater of the character described including spaced top and bottom plates, said top plate being permanently welded at its edges to the bottom plate, a perforated radiator plate arranged over the top plate in spaced relation thereto and having downwardly projecting flanges engaged upon the edge of said top plate, an insulating sheet engaged upon the bottom face of the base 95 plate, a metal sheet covering said insulating sheet and having its edges upwardly and inwardly bent and crimped upon the edges of said radiator plate to secure the latter in place, and an inlet pipe for the heating medium connected to one end of the base plate and an outlet pipe connected to the opposite end of said plate. 100

In testimony whereof I hereunto affix my signature in the presence of two witnesses.

JAMES R. CREIGHTON.
